UNITED STATES PATENT OFFICE.

CALVIN A. LEONARD, OF ROCHESTER, NEW YORK, ASSIGNOR TO JOHN H. HOPKINS, TRUSTEE, OF SAME PLACE.

DESIGN FOR A SALT-HOLDER.

SPECIFICATION forming part of Design No. 27,019, dated May 4, 1897.

Application filed March 18, 1897. Serial No. 628,224. Term of patent 7 years.

To all whom it may concern:

Be it known that I, CALVIN A. LEONARD, of Rochester, in the county of Monroe, in the State of New York, have invented and produced a new and useful Design for a Salt Holder or Receptacle for Salting Horses, Cattle, &c., of which the following is a specification, reference being had to the accompanying drawings, showing a part thereof.

10 Figures 1 and 2 are respectively top plan and side elevation of a salt holder or receptacle for salting horses, cattle, &c., embodying my design; and Figs. 3 and 4 are vertical sections taken, respectively, on lines 3 3 and 4 4, 15 Fig. 1.

The leading feature of my design consists in a salt holder or receptacle for salting horses, cattle, &c., which when viewed in top plan presents the appearance of one end of an ellipse subdivided by angularly-arranged bars and when viewed in elevation presents the appearance of a longitudinal half of one end of an ellipse.

A B C C D are respectively rear, front, 25 side, and bottom walls of a salt holder or receptacle embodying my design, and E E are intersecting bars rising from the bottom wall D and formed of less height than the walls A B C C. The rear wall A is substantially flat 30 and perpendicular and is provided with ears a a, which extend upwardly from the extremities of its top edge. The front wall B inclines rearwardly in opposite directions toward the side walls C C from its central portion b. The 35 lower portion b' of the wall B inclines downwardly toward the front end of the bottom wall D, and the upper edge of said wall B is substantially flat and is formed with an in-

wardly-projecting rib or shoulder b². The lower portions c c of the walls C C incline 40 downwardly toward each other, their front extremities c' c' are inclined forwardly toward each other and are united to the ends of the front wall B, and the upper edges of said walls C C are formed substantially flat 45 and are provided with inwardly-extending ribs or shoulders c² c². The central portion of the bottom wall D is formed with round perforations d, its front portion inclines upwardly toward the lower portion of the front 50 wall B, and its side portions are inclined upwardly in opposite directions and are united to the lower portions of the side walls C C. The intersecting bars E E are arranged at substantially right angles to each other between the round perforations d, extend lengthwise and crosswise above the bottom wall D, 55 and are formed of less height than the side walls C C.

A salt holder or receptacle for salting 60 horses, cattle, &c., embodying my design presents a graceful, pleasing, and characteristic appearance.

What I claim is—

The design for a salt holder or receptacle 65 for salting horses, cattle, &c., substantially as herein shown and described.

In testimony whereof I have hereunto signed my name, in the presence of two attesting witnesses, at Syracuse, in the county of 70 Onondaga, in the State of New York, this 27th day of February, 1897.

CALVIN A. LEONARD.
